[57] CLAIM

The ornamental design for a lavatory, as shown and described.

DESCRIPTION

FIG. 1 is a perspective view taken from the top and front of a lavatory embodying our new design;

FIG. 2 is a front elevational view thereof;

FIG. 3 is a right side elevational view thereof, the left side being the mirror image of the right side;

FIG. 4 is a top plan view thereof;

FIG. 5 is a bottom plan view thereof;

FIG. 6 is a rear elevational view thereof;

FIG. 7 is a cross-sectional view taken on line 7—7 of FIG. 4; and,

FIG. 8 is a cross-sectional view taken on line 8—8 of FIG. 4.

The fragmentary broken line representations of a countertop in FIG. 1 and mounting holes in FIGS. 1, 4 and 5 are for the purpose of illustration only and form no part of the claimed design.
